MICROSCOPE

John T. Armbruster, Niagara Falls, N. Y., assignor to
American Optical Company, Southbridge, Mass., a voluntary association of Massachusetts

Application February 26, 1957, Serial No. 44,992

Term of patent 14 years

(Cl. D57—1)

Figure 1 is a perspective view of a microscope, showing my new design. This view is taken from one side and forwardly of the microscope.

Figure 2 is a perspective view taken from the other side and rearwardly of the microscope, the prism housing and the oculars being shown in the forward position as viewed in Fig. 1.

The top of the prism housing of the microscope is substantially flat and of conventional configuration; the adjacent sides of the housing, not shown, are the same as the sides shown, except that the rear of the housing immediately below the angular top portion is plain.

The dominant features of my design reside in the portions shown in full lines in the drawing.

I claim:

The ornamental design for a microscope, substantially as shown and described.
